UNITED STATES PATENT OFFICE

ARTHUR L. REMINGTON AND RAYMOND C. LONGVALL, OF WORCESTER, MASSACHUSETTS, ASSIGNORS TO WARP COMPRESSING MACHINE COMPANY, OF WORCESTER, MASSACHUSETTS, A CORPORATION OF MASSACHUSETTS

SPINDLE MOUNTING FOR CREELS

Application filed April 11, 1927. Serial No. 182,923.

Our invention relates to creels or spool stands such as are employed for supporting a plurality of spools or yarn packages so that yarn or thread may be evenly led from the packages for winding on a warp beam, or for any other purpose.

Our invention relates particularly to that type of creel in which the yarn or thread is drawn from the ends of the packages in the general direction of the longitudinal axes of the packages, this type of creel being distinguished from the type in which the yarn or thread is drawn off tangentially to the periphery of the packages. In that type of creel to which our invention relates, difficulties have been heretofore encountered in doffing and replenishing spindles owing to the fact that the thread is being drawn off endwise of the spindles and consequently the operator must work very carefully when doffing in order not to interfere with the threads from the active spindles.

The object of our invention is to provide an improved mounting so arranged that an exhausted spindle can be withdrawn from its normal position in a row of active spindles and then turned back on itself to point in a direction which is opposite to the active spindles. This permits an exhausted package to be removed end wise and a fresh package substituted therefor without in any way interfering with the row of threads from the active spindles. The replenished spindle can then be turned back and thread drawn therefrom endwise without in any way interfering with the other active spindles. The above and other advantageous features of our invention will hereinafter more fully appear, reference being had to the accompanying drawings in which—

Fig. 1 is a perspective view of a portion of a creel provided with spindles mounted in accordance with our invention.

Fig. 2 is a plan view showing one of the

spindles with a fresh package placed thereon after doffing.

Fig. 3 is a fragmentary plan view showing one of the spindle mountings on an enlarged scale.

Fig. 4 is a fragmentary view showing the spindle mounting in side elevation.

Like reference characters refer to like parts in the different figures.

Referring first to Fig. 1, a portion of a creel stand is illustrated therein, which consists of a base member 1 having spaced uprights 2, 2, extending vertically therefrom. Although only a pair of uprights 2 are shown in Fig. 1, it is obvious from Fig. 2 that the number of uprights 2 can be increased to take care of any desired number of spindles.

As shown in Figs. 1 and 2, one pair of spindles 3, 3 are shown as carrying substantially full yarn packages 4, from which the threads 5 are drawn endwise, each pair of spindles 3 being supported in convergent relation so that the threads 5 meet at a common point, not shown, in front of the creel, see Fig. 2. The pair of spindles 3a, 3a below the active spindles 3 are shown as having been exhausted and withdrawn preparatory to doffing and replenishment, and our improved spindle mounting which permits this withdrawal will now be described.

As best shown in Fig. 3, each spindle 3 is received at one end in a fixture 6 which carries a shaft 7 rotatably mounted in the flanges 8 of a channel shaped bracket 9. The bracket 9 is in turn supported by spaced parallel rods 10 slidably mounted in the flanges 2a of the upright 2. The brackets 9 are secured to the rods 10 by nuts 11 and the opposite ends of the rods 10 are provided with stops 12 to limit the movement of the rods 10 on the upright 2 when the brackets 9 are withdrawn, as shown for the lower pair of spindles 3a in Fig. 1.

When a pair of spindles 3 are in their for-

ward or active positions they are slightly inclined upwardly to hold the yarn packages 4 thereon, and each spindle 3 is maintained in this uptilted position by means of a flange 5 attached to the spindle fixture 6. As shown in Fig. 4, this flange 13 is provided with a slot 14 which receives a pin 15 projecting from the near flange 8 of the bracket 9 to limit pivotal movement of spindle 3 and hold it in an upwardly inclined position when facing either forward or backward. In order to adjust the spindle 3 when facing forward, the fixture 6 provides an ear 16 carrying a stud 17 which engages the pin 15 and so permits the inclination of the spindle 3 to be exactly determined.

The lower pair of spindles 3a are shown as having been exhausted and the corresponding brackets 9 are shown as having been withdrawn to move the spindles 3a to their doffing position. Obviously, the withdrawal of a spindle 3a is effected without in any way interfering with the threads leading from the active spindles 3 above or below the spindles 3a, and after the brackets 9 have been moved to the position shown, the spindles 3a can be turned through an angle of substantially 180°, as shown in dotted lines in Fig. 1 and at the right in Fig. 2. In 20 the doffing position the pin 15 engages the end of the slot 14 and so limits the downward pivotal movement of the spindle 3a and it is evident from Fig. 2, that after removing the remainder of a package from a spindle 3a, a fresh package 4 can be readily slipped endwise on the spindle.

The replenished spindle is then turned back to the full line position shown in Fig. 1 and the bracket 9 pushed forward on the upright 2 to bring the spindle again to an active position directly below the spindle 3. Before a replenished spindle has been returned to the row it is an easy matter for the operator to lead the yarn over its end 40 through a suitable thread guide to the warp beam, or other winding device with which the creel is being used. It is to be noted particularly that all the operations for doffing and replenishing can be readily performed by the operator in the rear of the active spindles 3, so that the operator may work with entire freedom and greater speed than has been heretofore possible with creels of the type in which the thread is drawn over the ends of the packages.

From the foregoing, it is apparent that by our invention we have provided an improved spindle mounting for creels that is particularly advantageous when used in connection 50 with a creel of the type in which the yarn is drawn from the ends of the spindles. Our invention permits any of the spindles to be quickly doffed and replenished without in any way interfering with the end delivery 60 of the yarn by the active spindles, the whole

operation of doffing and replenishment being carried on in a space behind the active spindles, where the operator has opportunity for quick work.

We claim:

1. In a spindle mounting for creels, a vertical support, a bracket slidably mounted on said support for horizontal movement, a spindle pivotally mounted on said bracket to occupy either an active yarn delivery or a doffing position, means for limiting the pivotal movement of said spindle in either direction of turning about its pivotal axis, to determine the active or doffing position of said spindle independently of the sliding movement of said bracket on said support. 70
2. In a spindle mounting for creels, a plurality of spindles, a fixed vertical frame member, means for slidably supporting a series of said spindles on said frame member whereby any one of said spindles may be withdrawn from its active yarn delivery position, and means for pivotally supporting a withdrawn spindle in a position in which the spindle may be turned to point in the opposite direction for the purpose of doffing. 75
3. In a spindle mounting for creels, a spindle, a fixed frame member, means for slidably supporting said spindle on said frame member to permit its withdrawal from its active position and further means for pivotally supporting said spindle with respect to said frame member to permit said spindle to be turned and reversed for doffing. 80
4. In a spindle mounting for creels, a spindle, a carrier for supporting said spindle so as to present a full yarn package for the endwise removal of yarn therefrom, said carrier being so mounted that it may be slidably withdrawn in a direction opposite to that in which the spindle is pointing, and said spindle being so mounted on the carrier that in its withdrawn position the spindle may be turned to permit doffing while pointing in a direction opposite to that in which the yarn is drawn from the package on said spindle. 85
5. In a spindle mounting for creels, a plurality of spindles, a plurality of carriers for said spindles, a member for supporting a plurality of said spindle carriers so that yarn may be withdrawn endwise from packages on said spindles, and means for slidably mounting each carrier on said supporting member, whereby any one of said spindles, with its carrier, may be withdrawn from its active yarn delivering position to an inactive position, for doffing, without disturbing any of the remaining active spindles supported on said member by said carriers. 90
6. In a spindle mounting for creels, a plurality of spindles, a plurality of carriers for said spindles, a member for supporting said spindle carriers so that yarn may be drawn endwise from packages on said spindles, and means for slidably mounting 125

each carrier on said supporting member whereby any one of said spindles, with its carrier, may be withdrawn, with respect to the other spindles, in a direction opposite to that in which yarn is being drawn from said other spindles, each spindle being pivotally supported on its carrier to permit a withdrawn spindle to be reversed for the removal, or replacement, of a yarn package thereon.

10 Dated April 5, 1927.
